INVENTOR
William F. Hedberg
BY Arthur L. Braun

ATTORNEY

UNITED STATES PATENT OFFICE.

WILLIAM F. HEDBERG, OF KANSAS CITY, MISSOURI.

JOIST FORM.

Application filed November 22, 1926. Serial No. 149,954.

My invention relates to concrete forms and more particularly to a form for floor construction having joists of concrete.

It is a purpose of my invention to provide a form of the above mentioned character that is so constructed that the shoring can remain in place without disturbance of the same when the forms are removed, and a form wherein the minimum amount thereof must remain in place when the shoring is maintained in place and the remainder of the form removed. This is accomplished by providing soffit members that are sectional, small sections being provided above the posts used for shoring purposes that are only slightly larger in area than the tops of the posts, thus making it necessary to keep only these sections of the soffit members in place when the forms are removed prior to removing the shoring. The keeping of the shoring in place is a necessary procedure as the shoring must be left in position until the concrete has thoroughly set, while the forms can be removed and moved to another place after a much shorter period of time. Accordingly with my arrangement it is possible to use a much smaller number of forms than would otherwise be necessary with any other form previously known.

It is a further purpose of the invention to provide new and improved clamping means for holding the forms in position in assembling the same and also to provide new and improved means for mounting the stringers supporting the forms on the posts constituting the shoring.

Other objects and advantages of the invention will appear as the description of the accompanying drawings proceeds. However, I desire to have it distinctly understood that I do not intend to limit myself to the exact details shown or described, but that I intend to include as part of my invention all such obvious changes and modifications of parts as would occur to a person skilled in this art and as would fall within the scope of the claims.

In the drawings:

Fig. 1 is a perspective view, partly broken away, of a concrete floor, showing my improved forms in position for receiving the concrete.

Fig. 2 is a fragmentary sectional view of a floor, showing my improved form asso-

ciated therewith, portions thereof being shown in spaced relation thereto.

Fig. 3 is a fragmentary perspective view of a portion of a form showing an end closure member therefor, portions thereof being shown as being spaced from the form. 60

Fig. 4 is a transverse sectional view of the end closure member in position.

Fig. 5 is a fragmentary plan view of an end portion of a form showing the end 65 closure member in position.

Fig. 6 is a perspective view of a form clamp, and

Fig. 7 is a perspective view of a stringer 70 supporting clamp.

Referring in detail to the drawings:

My improved concrete form is mounted upon shoring comprising a plurality of post-like members 10 which have the bracket members 11 mounted thereon. Said bracket members are shown more clearly in Fig. 7 and comprise a U-shaped or yoke-like body portion 12 having a vertically extending portion 13 and a horizontally extending flange 14. The vertically extending portion 13 is provided with a pair of slots 15 adjacent one corner thereof through which a tapered wedge-shaped member 16 is adapted to be projected, said member being driven through the slots 15 into engagement with a corner of the post-like member 10 so as to bite into the same and hold the bracket member 11 firmly in position thereon. Extending through the oppositely located slots 17 in the parallelly extending portions of the member 12 are the tapering complementary wedge-shaped members 18 and 19, the member 18 having teeth 20 therein engaging with the post-like member 10 upon which the member 11 is mounted, the member 18 being wedged into engagement with the post-like member 10 by means of the member 19 and the member 19 being held in wedging relation thereto by the member 21 which is projected through the slot 22 in the flange 14. 80

Mounted upon the bracket members 11 and resting upon the flanges 14 thereof are the stringers 23. The stringers 23 support the substantially vertically extending members 105 24 which form the side members of the joist forms. The members 24 are provided with base portions 25 which rest on the stringers 23 and which project laterally from the member 24 in opposite directions, forming 110

the flanges 26 and 27 on said members 24, the flanges 27 extending inwardly toward each other and the flanges 26 extending outwardly away from each other. Thus each of the 5 members 24 is of an elongated inverted T shape. Resting upon the flanges 27 of the members 24 and mounted between paired members 24 are the soffit members 28. The upper end portions of the members 24 are 10 provided with the longitudinally extending members 29 having the beveled faces 30, thus providing overhanging grooves adjacent the upper end portions of the members 24. The paired members 24 are arranged in spaced 15 relation, as will be evident from Figs. 1 and 3 and the adjoining members 24 of adjoining pairs are held in proper spaced relation by means of the braces 31. Said braces are connected to one member 24 at one end thereof 20 by means of a hinge 32 and detachably connected with the other member 24 by means of a detachable connection comprising a strap member 33 formed into an eye and receiving the tongue 34 of the member 31, 25 the strap member 33 being mounted on the member 24.

The members 31 are preferably alternately arranged longitudinally of the members 24. That is, the hinges 32 and the straps 33 alternate along the length of each member 24 so that one member 31 is hinged to one member 24 while the adjoining member 31 is hinged to the opposite member 24. Engaging with the beveled faces 30 on the members 24 are the oppositely beveled ends 35 of the spaced members 36 which are supported by means of the braces 31 and which are bridged by means of the filler or bridging member 37 which is in turn supported by 30 means of the longitudinally extending member 38 supported by the braces 31. The dome portion of the form is thus formed by the members 36 and 37, and it will be obvious that the span thereof can be varied as desired by varying the width of the member 37. In a similar manner, the width of the joist portions of the form can be varied by varying the width of the member 28.

The members 28 are not continuous over the post-like members 10 but are provided with beveled end portions 39 spaced from the post-like members 10, and soffit members 40 having oppositely beveled end portions 41 are mounted upon the post-like members 10 extending only slightly beyond the side faces of said members 10 so that when the forms are removed as shown at the right of Fig. 2, the joist portion 42 of the concrete will be supported by the post-like members 10 and the small soffit members 40 will remain in place while all other parts of the form can be removed. This is a distinct advantage, as only very small blocks remain in place upon removal of the form in addition to the post-like members 10, thus mak-

ing it possible to retain the shoring in position without waste of material used for making the form. Preferably a pair of ribs 43 is provided running lengthwise of each of the joist forms and located at the opposite outer faces of the paired members 24, said ribs being formed by securing longitudinally extending members to the outer faces of the member 24 and serving to support the braces 31. Additional braces 44 are preferably mounted between the members 24 and resting upon the outwardly directed flanges 26 on the members 24. 70 75

In the form of concrete construction shown in the drawings the joists run between beams 80 which are of much heavier construction and in order to close the ends of the spaces between the joists at the beams, the end closure members shown in detail in Figs. 3, 4 and 5 are provided. In order to hold the end closure members in position, the vertically extending ribs 45 are provided at the ends of the members 24 which have the beveled faces 46 with which the oppositely beveled ribs 47 on the end closure members 48 and 49 engage. The end closure members comprise a relatively short member 48 and a relatively longer member 49 which are oppositely beveled at their adjoining ends to thus provide a tight joint at this point, said beveled ends 95 and the beveled ribs further holding said members 48 and 49 from outward movement. The straps 50 and 51 are provided on the members 48 and 49 respectively to hold the members 48 and 49 from relative horizontal 100 movement, and the members 25 are provided with projecting ends 52, thus providing flanges 53 upon which the members 48 and 49 rest. Said members 48 and 49 are held from inward movement by means of the 105 transversely extending bars 54 and 55 which engage in back of the blocks 56 and 57 respectively provided on the members 24 adjacent the members 48 and 25. The members 54 and 55 engage with the vertically extending strips 58 on the member 48 and the vertically extending strips 59 on the member 49, 110 as well as with the beveled strips 47.

In assembling the forms in order to hold the joist forming portions thereof in proper 115 position, suitable clamping means is provided comprising the horizontally extending member 60 adjustably mounted on one of the members 25 by means of the screw 61 extending through the slot 62, said member being adapted to be passed through an opening in the form of a slot in the eye member 63 mounted on the other member 24, said member 60 having a plurality of openings 64 therein which may be arranged 120 in staggered relation and which are adapted to receive the wedge pin 65 for firmly holding the form in the position shown in Fig. 2.

Instead of using the form of clamp de- 125

scribed above the clamp shown in Figs. 1 and 6 may be used, comprising the L-shaped members 66 and 67, the member 66 being angular in cross section and the member 67 being flat. The upstanding portions of the members 66 and 67 engage with the opposite sides of the members 24 and are held in clamping relation thereto by means of the wedge pins 68 which are adapted to be passed through aligning slots 69 and 70 in the transversely extending portions of the members 66 and 67, the members being guided in their relative movement by means of the flange 71 on the transversely extending portion of the member 66 engaging with the top edge portion of the transversely extending portion of the member 67. Suitable openings 72 may be provided in the member 66 through which securing devices may be passed for securing the upright portions of the clamping members to the members 24.

In taking down the forms the members 31 are first removed as shown at the left of Fig. 2, thus releasing the longitudinally extending members 38. The bracket members 11 are then removed whereupon the members 36 and 37 can be removed. After the members 36 and 37 are removed the clamps are released from the joist portions of the form whereupon the members 24 and the members 28 can be removed. The members 40 are, however, retained in position over the posts 10, thus providing shoring for the floor 73 by supporting the joist portions 42 thereof.

What I claim and desire to secure by Letters Patent is:—

1. In a joist form, a pair of side members having transversely extending base portions providing inwardly and outwardly directed flanges, a soffit member supported by said inwardly directed flanges, and braces engaging said outwardly directed flanges.

2. In a concrete form, a pair of substantially vertically extending members having undercut grooves adjacent the upper ends thereof, braces extending between said members, a pair of spaced members having bevelled ends engaging said undercut grooves and a filler member bridging the space between said spaced members.

3. In a concrete form, a pair of substantially vertically extending members having undercut grooves adjacent the upper ends thereof, braces extending between said members, a pair of spaced members having bevelled ends engaging said undercut grooves and a filler member bridging the space between said spaced members, said spaced members and said filler member being supported by said braces.

4. In a concrete form, a pair of substantially vertically extending members, braces extending between said members, a pair of

spaced members, engaging said vertically extending members, and a filler member bridging the space between said spaced members.

5. In a concrete form, a pair of substantially vertically extending members, braces extending between said members, a pair of spaced members engaging said vertically extending members, and a filler member bridging the space between said spaced members, each of said braces being hinged to one of said vertically extending members and detachably connected with the other thereof.

6. In a concrete form, paired vertically extending members having base flanges extending in opposite directions, soffit members mounted between said paired members and engaging certain of said flanges, braces extending between the vertically extending members of adjoining pairs, a pair of spaced members engaging the adjoining vertical members of adjoining pairs and a filler member bridging the space between said spaced members.

7. In a concrete form, paired vertically extending members having base flanges extending in opposite directions, soffit members mounted between said paired members and engaging certain of said flanges, braces extending between the vertically extending members of adjoining pairs, a pair of spaced members engaging the adjoining vertical members of adjoining pairs and a filler member bridging the space between said spaced members, said spaced members and said filler member being supported by said braces.

8. In a concrete form, post-like members, paired substantially vertically extending members, means on said post-like members for supporting said vertically extending members, soffit members mounted between said vertically extending members, and soffit members mounted over the ends of said post-like members.

9. In a concrete form, post-like members, paired substantially vertically extending members, means on said post-like members for supporting said vertically extending members, soffit members mounted between said vertically extending members, and soffit members mounted over the ends of said post-like members, said last mentioned soffit members extending only slightly beyond said post-like members.

10. In a concrete form, paired substantially vertically extending members and end closure members for said forms extending between said vertical members, means for holding said end closure members in horizontal alignment and means for holding said end closure members against inward movement.

11. In a concrete form, paired substan-

- tially vertically extending members and end closure members for said forms extending between said vertical members, said closure members and vertical members having engaging bevelled rib members thereon, means for holding said end closure members in horizontal alignment and means for holding said end closure members against inward movement.
- 10 12. In a joist form, a pair of side members having transversely extending base portions providing inwardly directed flanges, a soffit member supported by said flanges, and clamping means therefor comprising a member having a horizontally extending portion provided with a plurality of openings, a member engaging therewith and a wedge member insertable in an appropriate one of said openings to hold said members in clamping position.
- 15 13. In a joist form, a pair of side members having transversely extending base portions
- 20
- 25
- 30
- 35
- 40
- providing inwardly directed flanges, and clamping means therefor comprising a member having a horizontally extending portion provided with a plurality of openings, a loop member engaging therewith and a wedge member insertable in an appropriate one of said openings to hold said members in clamping position.
14. In a joist form, a pair of side members having transversely extending base portions providing inwardly directed flanges, a soffit member supported by said flanges and clamping means therefor comprising a pair of angular members having upstanding portions engaging opposite sides of said form and transversely extending portions having openings therein and wedging means insertable in an appropriate pair of said openings to hold said members in clamping position.

In testimony whereof I affix my signature.

WILLIAM F. HEDBERG.
